No. 625,402.

Patented May 23, 1899.

D. H. LENTZ.

FURNACE.

(Application filed Nov. 22, 1897.)

(No Model.)

UNITED STATES PATENT OFFICE.

DAVID H. LENTZ, OF JOLIET, ILLINOIS, ASSIGNOR TO THE MCKENNA STEEL WORKING COMPANY, OF MILWAUKEE, WISCONSIN.

FURNACE.

SPECIFICATION forming part of Letters Patent No. 625,402, dated May 23, 1899.

Application filed November 22, 1897. Serial No. 659,478. (No model.)

To all whom it may concern:

Be it known that I, DAVID H. LENTZ, a citizen of the United States, residing at Joliet, in the county of Will and State of Illinois, have 5 invented a certain new and useful Improvement in Furnaces, (Case No. 1,) of which the following is a full, clear, concise, and exact description, reference being had to the accompanying drawings, forming a part of this specification.

My invention relates to improvements in reverberatory furnaces, and has for its object the production of means for securing more efficient and equable heating throughout the 15 heating-chamber of a furnace.

My invention is more particularly applicable to a reverberatory furnace for evenly heating large objects, such as railroad-rails, and my said invention will be described in connection with a furnace of this class.

Hitherto heating-furnaces have been constructed wherein the treated metal of small bulk could be evenly heated throughout its mass; but such furnaces when constructed 25 upon a large scale were not capable of evenly heating railroad-rails throughout their entire length, which is necessary when the same require rerolling or being otherwise worked in a heated condition. As the standard length 30 of railroad-rails is thirty feet, it has accordingly been my purpose to devise a furnace of large proportions which, however, would be capable of economically producing and maintaining in all portions of its heating-chamber 35 a uniform or substantially uniform temperature. This I have been able to attain by the construction herewith shown and described, in connection with which I will set forth the features of my invention, which will be more 40 readily comprehended by reference to the accompanying drawings, wherein—

Figure 1 is a plan view of the furnace in section. Fig. 2 is a vertical sectional view thereof on line 2 2 of Fig. 1. Fig. 3 is an 45 other vertical section on line 3 3 of Fig. 1. Fig. 4 is a similar view on line 4 4 of Fig. 1.

The same letter of reference is used throughout the several figures to designate similar parts.

50 The furnace is provided with two fire-boxes

or combustion-chambers *a*, situated upon one side and near the ends of the heating-chamber *b*. Doors *a'* are provided, through which the fuel employed is passed to the hearths *a''*. The rear hearth-wall *a'''* extends slightly above 55 the doors *a'*. The flues *a''*, affording communication between the fire-boxes and the heating-chamber, extend the entire length of said fire-boxes, before which fire-bridges *c* are disposed within the heating-chamber and extend 60 considerably beyond the flue *a''* at a diagonal with the hearth-wall. The fire-bridges are slightly separated from the hearth-walls and extend centrally almost to the top of the flue-openings *a''*, sloping away at either end, as is 65 most clearly shown in Fig. 2.

Centrally disposed within the heating-chamber and extending across the same from side to side in the position of greatest rise of its upwardly-sloping roof is provided the fire-arch *d*. (Shown in Figs. 3 and 4.) The arch-opening rises a short distance above the charging-floor *d'*, whereon the rails are placed for heating within the chamber *b*. The fire-arch is adapted to direct downwardly and laterally the currents of flame and heated gases entering said chamber through the flue-openings after their dispersion by the fire-bridges and their expansion within the heating-chamber. At either end of the heating-chamber 75 are the charging gates or openings *f*, through which the said rails or other product to be treated are passed to the interior of said heating-chamber. Doors or slides *g* are hung before said openings and adapted to be simultaneously operated by means of the connected bell-crank arms *g'*, from which the said doors are hung. Counterweight *g''* is provided upon one of said bell-crank arms to balance 80 the weight of the doors or slides. 90

As shown more clearly in Fig. 3, the heating-chamber is connected with the chimney-stack *h* through the flues *i i'*, provided at either side of said chamber beneath the ends of the fire-arch *d*. Flue *i'* connects with the 95 said chimney-stack through the underdraft-flue *i''*, passing beneath the floor of the heating-chamber. Dampers *k k'* are situated in flues *i i'*, respectively. I have shown, somewhat diagrammatically, in the chimney-stack 100

the foundation and lower portion of a water-tube boiler, which, however, form no part of my present invention and will require no description in this specification. The fire-boxes 5 are provided with both hot and cold blast, the supply-pipes *l* being connected with a source of air under pressure and extending to the twyers *m* and *n*, which are respectively controlled by the valves *m'* and *n'*. The supply 10 pipes for the twyers *n* extend through the walls of the fire-boxes *a*, whereby the air is heated before being forced within the combustion-chamber.

The operation of the furnace of my invention 15 is as follows: The slides *g* being raised, the rails are slid into position upon the floor of the heating-chamber and the slides are immediately closed. The blast is turned on the fire-boxes, the proportion of the hot and cold 20 blast being so adjusted as to drive the flame and heated gases with the assistance of the fire-bridges and fire-arch as equally as possible throughout the heating-chamber. As the heat increases within the chamber the operators 25 in charge of said furnace adjust the valves *m'* and *n'* of the blast, as well as the dampers *k* *k'*, so as to rectify any underheating or overheating liable to occur in any portion of the chamber. As is well known, the 30 combustion produced by a hot blast is violent and accompanied by little flame but very intense heat, whereas that produced by a cold blast is more gradual, while the flame is very greatly increased, and thus by adjusting the 35 valves controlling the blasts the operators may generally direct the heating in any portion of the chamber. In addition by opening and closing the dampers *k* *k'* to a greater or less degree the passage of the heated gases 40 and flame is controlled. Thus the flames are driven over the fire-bridges, which spread the same, as indicated by the arrows in the several figures, passing to the various portions of the heating-chamber, and finally are directed downward centrally in said chamber 45 beneath the fire-arch to the flues *i* *i'*, from which exit is had to the chimney-stack. The fire-arch and fire-bridges serve to maintain the heated gases within the chamber for a 50 considerable length of time, so that a large percentage of the heat is utilized, and thus by controlling the said heating through the several means indicated the rails or other treated product are evenly heated throughout 55 their entire mass to the desired temperature. When this is attained, the slides before the charging-gates are thrown open and the heated rails may be removed from one end of the furnace while others are being placed 60 within the heating-chamber at the other end. Thus the furnace is capable of being rapidly operated at its full capacity.

It is apparent that alterations may be made in the structure herein shown and described, 65 as indicated in the accompanying claims, without departing from the spirit of my in-

vention, and I accordingly desire to secure, together with all such modifications, the following:

1. The combination in a furnace, with a 70 heating-chamber, of a fire-box, a communicating flue connecting the said fire-box and heating-chamber, and a fire-bridge disposed before the said flue, the said bridge extending approximately to the top of the central 75 portion of the flue-opening and sloping downwardly at either end and adapted to direct the flame and heated gases upwardly and laterally within the heating-chamber, whereby an equal temperature is maintained in the 80 different portions thereof, substantially as described.

2. The combination in a reverberatory furnace, with a heating-chamber, of a fire-box or combustion-chamber associated therewith, a 85 flue-opening affording communication between said heating-chamber and fire-box, means for supplying an air-blast to the said fire-box, and a fire-bridge disposed before the flue-opening extending centrally to the approximate height of the opening, the safe-bridge sloping downwardly at either end thereof, whereby the flame and heated gases from the fire-box are distributed throughout the heating-chamber, substantially as described. 90

3. The combination in a furnace of the class described, with a heating-chamber, of a fire-box or combustion-chamber associated therewith, a flue-opening affording communication 100 between the said chambers, a second flue-opening affording communication with the chimney-stack of the furnace, and a fire-bridge disposed before the said flue-opening extending diagonally and sloping downwardly therefrom adapted to direct the flames and heated gases in the general direction of the second-named flue-opening, substantially as described. 105

4. In a reverberatory furnace, the combination with a heating-chamber, of a fire-box, a communicating flue connecting the said fire-box and heating-chamber, and a fire-bridge disposed before the said flue, the said bridge extending approximately to the top of the central portion of the flue-opening and sloping downwardly at either end, whereby the flame and heated gases from the said fire-box are distributed throughout the heating-chamber, substantially as described. 110 115

5. The combination in a furnace, with a heating-chamber, of a fire-box or combustion-chamber associated therewith and opening into said heating-chamber, a fire-arch situated within said heating-chamber, and a flue 120 opening or openings communicating with the chimney-stack of the furnace disposed beneath and at the ends of the said fire-arch, adapted to direct the heated gases and flame within the chamber downwardly and laterally to the said chimney-stack, substantially as described. 125 130

6. In a reverberatory furnace, the combination with a heating-chamber, and a fire-box or combustion-chamber associated therewith, of means for supplying an air-blast to said combustion-chamber, a flue affording communication between the said fire-box and heating-chamber, a fire-bridge disposed before the flue, a fire-arch situated within the heating-chamber, and flues disposed at the bottom of said heating-chamber beneath and at the ends of the arch, whereby the heated gases and flames entering by way of the flue are directed throughout the chamber to secure an equal temperature therein, substantially as described.
7. In a reverberatory furnace, the combination with a heating-chamber, of fire-boxes associated therewith and near each end thereof, means for supplying an air-blast to said fire-boxes, flues affording communication between the said fire-boxes and heating-chamber, fire-bridges disposed before the flues, a fire-arch centrally situated within the heating-chamber, flues disposed at each side of the bottom of the heating-chamber and communicating with the chimney-stack, and means for controlling the passage of the heated gases through said flues, substantially as described.
8. In a furnace of the class described, the combination with a heating-chamber *b*, of fire-boxes *a* disposed upon a side and near the ends of said heating-chamber, communicating flues *a'*, fire-bridges *c* arranged before the communicating flues of said fire-boxes, a fire-arch *d* centrally disposed within said heating-chamber, and flues *i i'* disposed beneath

said fire-arch at each side of the chamber and affording communication with the chimney-stack of the furnace, substantially as described.

40

9. In a furnace, the combination with fire-boxes *a a*, of means for supplying and controlling hot and cold blasts within the said fire-boxes, a heating-chamber *b* near the ends of which the said fire-boxes are situated, communicating flues *a'*, fire-bridges *c* disposed before said flues, a fire-arch *d* disposed in the heating-chamber between the said fire-bridges, and flues *i i'* situated at the base of the fire-arch at each side of the chamber and communicating with the chimney-stack of the furnace, substantially as described.

45

10. In a furnace of the class described, the combination with a fire-box or combustion-chamber, of a heating-chamber communicating therewith adapted to secure the expansion and equal distribution of the heated product entering from said fire-box, a flue adapted to afford such communication, a fire-bridge disposed before a portion of the flue-opening, a fire-arch situated within the heating-chamber and openings communicating with the chimney-stack disposed in the lower portion and at each side of said heating-chamber beneath the arch-opening, substantially as described.

50

In witness whereof I hereunto subscribe my name this 18th day of November, A. D. 1897.

DAVID H. LENTZ.
